UNITED STATES PATENT OFFICE.

PETER BEGHETTI, OF SAN FRANCISCO, CALIFORNIA.

ACTUATING MECHANISM FOR AIR-BLOWN MUSICAL INSTRUMENTS.

Application filed December 23, 1925. Serial No. 77,236.

This invention relates to air blown instruments such as a harmonica or the like and especially to a mechanism whereby air may be delivered to the several reeds to sound the scale.

The object of the present invention is to provide a device of the character described which may be used as a noise maker during carnivals, New Year's eve celebrations or like 10 festive occasions and which may also serve as a substitute for a horn on an automobile.

The invention, briefly stated, comprises a mounting for the instrument such as a harmonica in which the instrument may be rigidly supported, a member slidably mounted with relation to the air inlet openings of the harmonica and a bellows or like device connected with the said member to deliver air and thereby sound the instrument.

One form which the invention may assume is illustrated in Figs. 1 and 2 in which—

Fig. 1 is a side elevation of a mounting supporting a harmonica and a mechanism whereby air is delivered to actuate the harmonica.

Fig. 2 is a cross section taken on line 2—2 of Fig. 1.

Referring to the drawings in detail and particularly Fig. 1, A indicates in general an angle bracket consisting of an upright portion 2 and a base portion 3. Clamped to the upright portion by means of brackets 4 and 5 is a harmonica 6. Slidably mounted on the harmonica is a member generally indicated at 7. This member consists of side sections 8 see Fig. 2 and a back section 9. Secured to the side sections are spring members 10 and 11. These members, together with the side sections 8—8 and the end section 9 form an elongated surrounding guide which is freely slidable in a vertical direction on the body of the harmonica. The front of the harmonica is provided with a plurality of air inlet openings such as indicated at 12 and the sliding member passes over the openings when reciprocated.

Formed in the members 10 and 11 is a central opening 14 and extending through the opening is a flanged mouth piece 15 which is held in frictional contact with the front face of the harmonica. Attached to the flanged mouth piece is a rubber bulb 16 and supporting the same is a cone-shaped helical spring 17 which is secured to the base 3 as at 18.

If the device is to be used as a noise maker, 55 for instance, at a New Year's eve celebration it may be placed directly upon a table or other support, and the person operating the instrument merely squeezes the bulb and pushes downwardly against the tension of 60 the spring 17. The air is expelled when the bulb is pushed downwardly and squeezed and as the slide to which it is attached passes over the air inlet openings 12 it is obvious that the air will actuate the reeds indicated at 19 and thereby sound the different notes or tones of the scale. When the bulb is released the spring forces it upwardly and the bulb is refilled by its own expanding action. A harmonica works both by suction 70 and by air pressure and the notes are thus sounded both during the expelling action of the bulb and during the suction action of the same.

If the device is to be used on an automobile it may be placed where it may be conveniently reached by the operator or driver.

While the invention has here been described and illustrated in conjunction with a harmonica it is obvious that it may be connected with any other wind blown instrument if desired.

Having thus described my invention what I claim and desire to secure by Letters Patent is—

1. A combination with a musical instrument having a plurality of air admitting openings and cooperating mechanism whereby different tones are produced of a member 85 slidable with relation to said air inlet openings and air delivering means connected with said slide.

2. A device of the character described comprising a harmonica, a rigid support therefor, a member slidably mounted with relation to air openings formed in the harmonica and a rubber bulb connected with said member and adapted to deliver air to said openings as the member moves over the same.

3. A device of the character described comprising a harmonica, a support therefor maintaining it in a vertical position, a sliding member embracing the harmonica and forming a closure over the air inlet openings in the harmonica, a rubber bulb connected with said sliding member and adapted to be manually operated to deliver air to the open-

ings and means for normally holding the sliding member at the upper end of the harmonica..

4. A device of the character described comprising a harmonica, a support therefor maintaining it in a vertical position, a sliding member embracing the harmonica and forming a closure over the air inlet openings

in the harmonica, a rubber bulb connected with said sliding member and adapted to be manually operated to deliver air to the openings, a spring actuated means adapted to normally support the bulb and the sliding member in an elevated position on the harmonica.

PETER BEGHETTI.
